ELECTRICAL EGG COOKER, BOTTLE STERILIZER, AND THE LIKE

Daniel N. Peirce, Bethayres, Pa., assignor to Fox Products Company, a corporation of Pennsylvania

Application August 5, 1936, Serial No. 94,391

12 Claims. (Cl. 219—40)

This invention relates to liquid resistance conductor heating devices in which the water to be evaporated completes the circuit. These liquid conductor heating devices are useful for such purposes as egg cookers, bottle sterilizers, and the like.

The primary object of my invention is to provide a simple, compact and effective device of highly practical nature. The character and objects of my invention will be best understood from the following brief statement of some of the difficulties heretofore encountered in practice.

Some of the devices heretofore proposed are open to the objection that they are prone to accidental short circuiting. Others can be handled without likelihood of shock only if the switch is opened. Still others are so constructed that cleaning is impossible or so difficult that the parts are not cleaned and sediment short circuits them, and their useful life is thus greatly shortened. Again, in case of failure, the whole device had to be returned for repair.

In short, the previous devices for one reason or another, have been lacking in simplicity and practical characteristics, so much so that it has been difficult to secure reliable distributors to carry them because of the frequency of complaints.

I propose to overcome these difficulties by the construction shown in the accompanying drawing, wherein—

Figure 1 is a cross section through the base and electrode carrier members of a device embodying my improvements, a portion of the cap being shown in dotted lines and the section being on the line 1—1 of Figure 2.

Figure 2 is a plan view of Figure 1 with the cap removed.

Figure 3 is a side elevation of the electrode carrier member, and

Figure 4 is a bottom plan view of Figure 3, showing the electrodes.

Referring now to the drawing, the reference numeral 1 indicates the base proper of the device having recesses in its upper face so as to receive the electrode carrier member 8 and to provide a well 1a for the water to be evaporated. The base is provided with an annular rim or bead 10 adapted to receive and position the cover 9. The base is also provided with two recesses or apertures 1b serving to receive and house the spring clips 13 held in position by the terminal bolts 11 and 12. The nuts which secure the terminal bolts also serve to hold in position the in-

sulating strip 14. Another insulating plate 15 is located below and spaced from the strip 14 and carried by said strip through the medium of the stud 16. The insulating plate 15 thus closes the bottom of the device covering over the terminal bolts.

The cord 17 is led into the base through the aperture 1c.

The porcelain electrode carrier member 8 has two posts 18 adapted to be frictionally engaged by the spring clips 13 when the carrier member is pushed home to the position shown in Figure 1. The two electrodes 19 and 20 are each connected at one end to a terminal post 18, being secured by the nuts 21. The electrodes are each in the form of a spiral with the free ends abutting the central boss 22 of the carrier member, on opposite sides thereof. The carrier member is provided with spiral grooves 8a to freely receive the upper edge portions of the spiral electrodes. Thus the electrodes and the carrier constitute a self-contained unit, the electrodes coming away with the carrier when it is pulled out of place. At the same time the loose fit of the upper edges of the electrodes in the spiral grooves 8a formed in the carrier, permits the electrodes to vibrate, which is of advantage for expansion and other reasons hereinafter stated. Self setting insulating cement covers over the upper ends of the terminal posts 18 as indicated at 18a. Thus, one cannot, in handling the device, be accidentally shocked. Even with the carrier out of place, the clips 13 are so relatively inaccessible that one would almost have to deliberately go about short circuiting them.

The base and the carrier member are provided with complementary recesses 24 and 25 cooperating to provide circular recesses to receive the eggs. A plurality of small holes 26 extend through the carrier member so as to permit the steam formed to freely rise during the heating operation. Each recess 1b is in communication with the well 1a by providing connecting channels as indicated at 27.

It will be noted that the electrodes are almost wholly exposed, only the upper edge portions lying in the grooves in the carrier. It will also be noted that the lower edge of the electrodes is substantially above the bottom of the well 1a.

In operation the device functions as follows: A small quantity of water is introduced and quickly finds its way to the well and into the apertures 1b. The water completes the circuit and acts as a resistance conductor. The surface presented by the electrodes (each elec-

trode is about 9 inches in length and a quarter inch in width) for contact with the water is relatively quite extended and thus ensures rapid heating of the water. When the water has been evaporated the circuit is automatically broken. Since the device is practically fool-proof the main switch may be left closed and all that is necessary to make the device function is to add the desired amount of water.

10 Most of the sediment will naturally collect in the bottom of the well. Sediment depositing on the electrodes is largely shaken loose by the vibration of the coils, which takes place when the last of the water is being evaporated. The sediment shaken off falls to the bottom of the well, and since the lower edges of the electrodes are well above the bottom of the well and since the amount of sediment is small, it will be seen that the device can be in service for a long time before there is any likelihood of short-circuiting from accumulation of sediment.

15 Disassembly for cleaning purposes merely involves pulling out the carrier member. When this is done all of the surfaces can be readily cleaned by brushing.

20 The electrodes being anchored at the end and the turns in part lying within the grooves of the carrier member, the electrodes cannot contact with one another to produce short circuiting. All of the current carrying parts are effectively housed and protected against accidental injury and accidental short-circuiting. If the electrodes need to be replaced, a new carrier unit is substituted without the need of returning the 25 whole device to the shop.

25 Owing to the arrangement and area of the electrodes, the device begins to boil water almost instantly.

30 The vibration of the electrodes occurring when the last of the water is being operated, makes a humming sound, giving an audible indication that the operation is about complete. Another indication is the stoppage of discharge of steam from the small hole usually provided in the upper 35 portion of the cover.

35 The base proper 7 and the carrier member may be termed a two-part base.

40 It will also be noted that the carrier unit itself may be used as an immersion heater. This can be done by passing leading-in wires through a pair of the larger holes 26 at the periphery of the carrier member and connecting their ends to the respective terminal posts, whereupon the carrier member can be immersed in water for 45 immersion heating. The external configuration of the carrier may desirably be changed for such use.

45 I claim:

1. In a liquid conductor heater, the combination of a base having a well for the liquid to be evaporated, an electrode carrier member, a pair of electrodes carried by said member as a unit therewith the circuit of which is adapted to be completed by the liquid in the well, and means for detachably securing the carrier member to the base, the said electrodes being in the form of ribbons projecting downwardly from the lower face of the carrier member into said well.

50 2. In a liquid conductor heater, the combination of a base having a well for the liquid to be evaporated, an electrode carrier member, a pair of electrodes carried by said member as a unit therewith the circuit of which is adapted to be completed by the liquid in the well, and means for detachably securing the carrier member to

5 the base, the said electrodes being in the form of horizontally disposed and nesting spiral ribbons projecting downwardly from the lower face of the carrier member into said well but terminating short of the bottom of the well.

5 3. In a liquid conductor heater, the combination of a base having a well for the liquid to be evaporated, an electrode carrier member, a pair of electrodes carried by said member as a unit therewith the circuit of which is adapted to be completed by the liquid in the well, and means for detachably securing the carrier member to the base, the said electrodes being in the form of horizontally disposed and nesting spiral ribbons projecting downwardly from the lower face 15 of the carrier member into said well but terminating short of the bottom of the well and being anchored.

20 4. In a liquid conductor heater, the combination of a base having a well for the liquid to be evaporated, an electrode carrier member, a pair of electrodes carried by said member as a unit therewith the circuit of which is adapted to be completed by the liquid in the well, and means for detachably securing the carrier member to the base, the said electrodes being in the form of horizontally disposed and nesting spiral ribbons projecting downwardly from the lower face 25 of the carrier member into said well but terminating short of the bottom of the well and being anchored at their ends with freedom to expand and vibrate.

25 5. In a liquid conductor heater, the combination of a base having a well for the liquid to be evaporated, an electrode carrier member, a pair of electrodes carried by said member as a unit therewith the circuit of which is adapted to be completed by the liquid in the well, and means for detachably securing the carrier member to the base, the said electrodes being in the form 30 of horizontally disposed and nesting spiral ribbons projecting downwardly from the lower face of the carrier member into said well but terminating short of the bottom of the well and being anchored at their ends with freedom to expand and vibrate.

35 6. In a liquid conductor heater, a base having a well, upwardly open spring terminal clips carried thereby, and an electrode unit comprising a carrier member insertable in the well, a pair of spaced electrodes carried thereby at the lower face 40 thereof to have their circuit closed by the liquid in the well, and a pair of terminal posts therefor presented downwardly and adapted to be frictionally held by the spring clips.

45 7. In a liquid conductor heater, a base having a well, spring terminal clips carried thereby, and an electrode unit comprising a carrier member insertable in the well, a pair of spaced electrodes carried thereby at the lower face 50 thereof to have their circuit closed by the liquid in the well, and a pair of terminal posts therefor adapted to be frictionally held by the spring clips, said carrier member and base having substantially flush upwardly presented surfaces in a plane 55 below the upper edge of the base and the carrier member having recessed portions providing gripping surfaces.

60 8. In a liquid conductor heater, the combination of a base having a well for the liquid to be 70 evaporated, an electrode carrier member, a pair of electrodes carried by said member as a unit therewith the circuit of which is adapted to be completed by the liquid in the well, and means for detachably securing the carrier member to

- the base, the said electrodes being in the form of horizontally disposed and nesting spiral ribbons projecting downwardly from the lower face of the carrier member into said well but terminating short of the bottom of the well and being anchored at their ends with their intermediate portions free for limited vibration, the carrier member having spiral grooves receiving the said intermediate portions of the electrodes.
- 5 9. In a liquid conductor heater, a two part base, the lower part of which constitutes a well for liquid and the upper part of which has electrode means incorporated therewith as a unit and disposed at the lower face thereof, electric current connections having terminal elements mounted on the lower part of the base, and cooperating terminal elements for the electrode means mounted on the upper part of the base, said terminal elements being disconnectible by 10 relative upward displacement of the upper part of the base.
- 10 10. In a liquid conductor heater, a two part base, the lower part of which constitutes a well for liquid and the upper part of which has electrode means incorporated therewith as a unit and disposed at the lower face thereof, electric current connections having terminal elements mounted on the lower part of the base, and cooperating terminal elements for the electrode 15 means mounted on the upper part of the base, said terminal elements including frictionally interengaging parts adapted to secure the two parts 20
- 25 30
- of the base together and being disconnectible by relative upward displacement of the upper part of the base.
11. In a liquid conductor heater, a base having an upwardly open chamber therein at least a part of which is adapted to receive a charge of liquid for evaporation, an electrode carrier member insertible into and removable from said chamber at its upper open side, spaced electrodes mounted on said carrier member and adapted to project into liquid in said chamber for completion of their circuit through said liquid, and cooperating disconnectible spring terminal clips and terminal posts mounted on the base and on the carrier member within said chamber.
- 15 12. In a liquid conductor heater, a base having an upwardly open chamber therein at least a part of which is adapted to receive a charge of liquid for evaporation, an electrode carrier member insertible into and removable from said chamber at its upper open side, spaced electrodes mounted on said carrier member and adapted to project into liquid in said chamber for completion of their circuit through said liquid, electric current connections associated with the base 20 and having terminal elements exposed in such chamber, and cooperating terminal elements for the electrodes mounted on the carrier member, said terminal elements being disconnectible upon upward displacement of the carrier member with 25 respect to the base.
- 30
